CLAIM

The ornamental design for a shoe as shown and described.

DESCRIPTION

FIG. 1 is a front bottom perspective view of a shoe showing my new design;

FIG. 2 is a bottom view thereof; and,

FIG. 3 is a rear bottom perspective view thereof.

The broken line immediately adjacent to the solid line defines the bounds of the claimed design and forms no part thereof. The unshaded areas form no part of the claimed design. The broken lines depicting the remainder of the shoe form no part of the claimed design.
